UNITED STATES PATENT OFFICE

CHAMPLAIN L. RILEY, OF NORTH PLAINFIELD, NEW JERSEY

MEANS FOR NEBULIZING FLUIDS

Application filed April 28, 1928. Serial No. 273,658.

This invention relates to the art of nebulizing or atomizing liquids.

In certain industries it is found desirable to atomize two streams of liquid simultaneously so as to permit interaction of the constituents in the resulting nebulized masses. This interaction may be a mingling of the dry products remaining after evaporation of the volatile constituents of the streams or a mingling of the volatile constituents themselves or of the dry and the volatile. It may also be a chemical interaction between the volatile constituents or between the volatile constituents of one stream and the solid constituents of another. In certain instances, the evaporation of one stream is used to cool the other stream.

An example is in the manufacture of powdered soap where a powdered silicate or a powdered soda-ash is to be mixed with the soap without combining the soap and the silicate or soda-ash in liquid form. By the simultaneous nebulization of a solution of the silicate or soda-ash and a stream of the liquid soap, the mingling of the dry solid constituents is effected and the liquid constituents are evaporated.

Another example is in the preparation of a solid granular tar product. Such a product may be obtained by the simultaneous nebulization of a stream of hot tar and a stream of cold water in close proximity so that the resulting nebulized masses may be intimately intermixed.

It is an object of this invention to provide an apparatus by which the simultaneous atomization or nebulization of separate streams of liquid may be effected and by which nebulized masses may be created in such proximity as to permit interaction, chemical or otherwise, between the constituents of these masses.

It is also an object to provide an apparatus which, being capable of effecting the above object, will be of simple construction, easily assembled and efficient in use.

In the preferred embodiment of the invention, a centrifugal spray bowl is provided in which there is space for radial flow of two separate streams and in which separate cone

faces, one extending downward, and the other upward, are placed in the path of these radial streams. Such a structure is described more particularly hereinafter with reference to the accompanying drawings, in which

Fig. 1 is a plan view of a centrifugal spray bowl embodying the present invention, and

Fig. 2 is a sectional view taken on the line 2—2 of Fig. 1.

To the spindle 1, which is adapted to be driven at high speed by a turbine or belt in the known manner, is attached the spray bowl 2, by means of a bolt 3. The bolt 3 extends through a washer 3' and a ball 4 which forms part of the bowl 2, the washer engaging the ball on the under side and the bolt being threaded into the spindle 1 to secure the bowl for rotation with the spindle.

The bowl 2 further consists of a radial plate 7 having a series of holes 8 therethrough near the ball 4 and spaced on a circle concentric with the spindle. Radially beyond this series of holes is a mid-baffle 6 upstanding on the upper face of the plate 7 and inclined inwardly. At the outer end of the plate 7 are flanges forming a peripheral baffle 9 extending above and below the plate 7. The inner faces of this baffle are inclined outwardly both above and below the plate. The upper and lower edges of this baffle 9 form the discharge lips.

A ring 12 is secured to the upper face of plate 7 by bolts 14. The outer face of this ring is inclined to conform to the inclination of the upper part of baffle 9 and the inner face is oppositely inclined, as shown in Fig. 2, substantially parallel to baffle 6. A bead 15 on the ring 12 fits in a recess in the plate 7.

At spaced points in the ring 12 are angled passages 13 leading from the space between the conical baffle 6 and the ring, first radially outward and then upward and outward, ending in ports of relatively small radial dimension as compared with the arcuate dimension.

These passages preferably are formed as recesses in the outer surface of the ring 12, as shown, so that the baffle 9 forms one wall of the flow passage.

Above the spray bowl and concentric with the spindle are three sleeves, the inner one

terminating between the spindle and the conical baffle 6 so as to provide an annular channel 16 opening into the space between the baffle 6 and the spindle. The sleeves 10 and 11 both terminate between baffle 6 and ring 12 so as to provide a channel 17 opening into the space between the baffle and the ring. These channels are in communication with separate sources of liquid supply.

10 In operation, the spindle is rotated at high speed and liquid is supplied to the separate channels 16 and 17. The stream from channel 17 is deflected outward by baffle 6 and is caused to rotate, the centrifugal force generated thereby causing the liquid to flow with some force into passages 13 where further centrifugal force is generated, causing the discharge of the liquid in a fine mist or nebulized mass from the discharge lip.

20 The liquid delivered from channel 16 is received in the space between the spindle and a baffle 6 where it is caused to rotate. Until it attains substantially the speed of the bowl itself, no liquid passes through openings 8 but upon attaining it, the liquid passes through and is impelled radially along the under face of plate 7 against baffle 9 which deflects it downward until it is discharged from the lip as a mist or spray forming another nebulized mass.

25 Thus two nebulized masses are created simultaneously and in close proximity. The solid constituents of the two masses, in dry condition, are free to mix. So also with the 35 volatile constituents and, depending upon the liquids introduced, various interactions may occur between the volatile and solid constituents.

I claim:—

40 1. Apparatus comprising a rotatable plate, a peripheral baffle thereon, a mid-baffle on one side of the plate, the plate being ported between its center and the mid-baffle, and fluid supply means for delivering separate streams 45 of fluid to said plate, one between the center and the mid-baffle, the other between the mid-baffle and the peripheral baffle.

2. A centrifugal nebulizer comprising a rotatable plate, a series of ports near the center 50 thereof, a conical baffle on one face thereof radially beyond the ports, a peripheral ring on one side of the plate having passages therethrough, and a peripheral baffle on the other side of the plate.

55 3. A centrifugal nebulizer comprising a web, a peripheral, axially-extending baffle affording a discharge lip, and a ring resting against the inner face of said baffle and the face of said web adjacent the baffle, said ring 60 having recesses, from its faces adjacent said web and baffle, providing flow passages from the inner region of said web toward said discharge lip.

65 4. A centrifugal nebulizer comprising a web, a series of ports therethrough, means at

the periphery of said web forming discharge lips on opposite sides thereof, and a means on one side of said web for preventing radial flow of liquid from the region of said ports to the discharge lip on that side of the web. 70

5. A centrifugal nebulizer comprising a web, a series of ports therethrough, a peripheral baffle extending axially on both sides of said web and means on one side of the web for preventing radial flow of liquid on that 75 side of the web from the region of said ports to the peripheral baffle.

6. A centrifugal nebulizer comprising a rotor having discharge lips in spaced planes, means for delivering separate fluid streams to 80 one side of said rotor and means for passing one of said streams to the opposite side of the rotor, whereby said streams are fed separately by centrifugal impulsion to said lips for dispersal as nebulized masses. 85

7. A centrifugal nebulizing rotor having discharge lips in spaced planes in combination with means for receiving separate bodies of liquid on one side of said rotor and means for centrifugally impelling said streams separately, one to each of said discharge lips, whereby said bodies of liquid are dispersed 90 separately in atomized form.

8. A centrifugal nebulizing rotor having a web with discharge lips on the opposite faces 95 of said web in combination with means for delivering to said opposite faces separate bodies of liquid to be nebulized for dispersal in adjacent planes, whereby they may commingle in nebulized form.

In testimony whereof I have signed my name to this specification.
